[57] CLAIM

The ornamental design for a cocked-neck bottle, as shown and described.

DESCRIPTION

FIG. 1 is a front elevational view of a cocked-neck bottle showing my new design;

FIG. 2 is a left-side elevational view thereof;

FIG. 3 is a bottom view thereof;

FIG. 4 is an enlarged fragmentary view of the neck portion taken along line 4—4 of FIG. 1; and

FIG. 5 is a right-side elevational view of the bottle of FIG. 1;

FIG. 6 is a back elevational view thereof; and,

FIG. 7 is a top plan view thereof.
